(57) **CLAIM**

The ornamental design for a power cord outlet, as shown and described.

DESCRIPTION

FIG. 1 is a front perspective view of a power cord outlet mounted on a merchandiser rack showing my new design;

FIG. 2 is a front elevational view thereof;

FIG. 3 is a top plan view thereof;

FIG. 4 is a bottom plan view thereof;

FIG. 5 is an another perspective view thereof;

FIG. 6 is a rear perspective view thereof;

FIG. 7 is a cross sectional view of FIG. 1 taken along the lines 7; and,

FIG. 8 is a close up view of the power cord outlet of FIG.

5, taken in circle 8.

In the drawings, the broken lines are for the purpose of illustrating environment only and form no part of the claimed design.
